F. A. RICH AND H. W. BASSETT, OF WALLINGFORD, CONNECTICUT, ASSIGNEES TO HALL, ELTON, AND COMPANY, OF SAME PLACE.

Letters Patent No. 79,004, dated June 16, 1868.

IMPROVEMENT IN DIES FOR CUTTING SPOON-BLANKS.

The Schedule referred to in these Letters Patent and making part of the same.

TO ALL WHOM IT MAY CONCERN:

Be it known that we, F. A. RICH and H. W. BASSETT, of Wallingford, in the county of New Haven, and State of Connecticut, have invented a new Improvement in Dies for Blanking Spoons; and we do hereby declare the following, when taken in connection with the accompanying drawings, and the letters of reference marked thereon, to be a full, clear, and exact description of the same, and which said drawings constitute part of this specification, and represent, in—

Figure 1, a perspective view of the die,

Figure 2 a perspective view of the punch inverted, and in

Figure 3, diagram showing the plan of blanking.

This invention relates to an improvement in cutting blanks for the manufacture of spoons. Heretofore, the blanks have been cut from a sheet of metal, by placing the sheet under proper dies, so as to cut from one edge only, then reversing the metal, so as to present the other edge. Other blanks were cut in like manner, thus using nearly all the metal in the sheet, but a separate operation is required for each individual blank. By our improvement, after the first blank is cut, every succeeding operation cuts two blanks, employing but a single die, and our invention, by which this is accomplished, consists in providing the die or punch with a cutter, in such relative position to the die that the said cutter will divide the blanks upon one edge, while the die proper cuts a series of blanks from the other edge, the blanks upon the opposite edge being formed by the space between the blanks upon the edge where the die operates.

To enable others to construct our improvement, we will proceed to describe the same as illustrated in the accompanying drawings.

A is a die-holder, constructed so as to receive and securely hold the die-plate B. Through the said die-plate B the die C is formed, of the shape required for the spoon-blank, and as denoted by broken lines at D, fig. 3, and upon the die-plate, in the proper relative position, (more fully hereafter shown,) we form an edge, a.

E is the punch, constructed to fit the die C, and fixed to a plate, F, and upon the said plate F is fixed a cutter, G, adjusted so that when the punch enters the die, the said cutter G will pass down across the edge a on the die-plate, so that the sheet placed between the two will be operated upon at the same time, both by the punch and cutter G.

The punch and die are arranged in a common punching-press, so as to operate in the usual manner.

The form of the die, as denoted at D, fig. 3, is such that one blank, formed by the die when reversed, corresponds, the one side to the other, as denoted in fig. 3, so that while the die forms the blank it at the same time forms one side of a blank, H, and the opposite side of a blank, I, but in so forming the blank, D, and the two sides H and I, it leaves the point J still connected; that is to say, the blanks upon the side D are entirely detached by the die, while those upon the opposite side are joined at J.

Having passed the sheet between the die, and punched therefrom, so as to form the outer edge of the blank, K, the sheet is fed along until the die will strike the plate, and punch a blank from the space L, thus forming the opposite side of the blank, K. Again fed along, the dies strike from the sheet another blank, D, and at the same time the cutter G separates the blank, K, by cutting through the sheet at M, and so continuing, each successive operation of the die striking a blank from one edge of the plate, and at the same time the cutter G separating the second blank at the opposite edge. Thus, by the arrangement of the cutter G, twice as much work is performed as by the machinery heretofore in use, and no waste of metal.

We make the cutter G adjustable, for the reason that constant use requires the cutter to be sharpened, and in that case readjustment is necessary.

Having thus fully described our invention, what we claim as new and useful, and desire to secure by Letters Patent, is—

The arrangement of the cutter G on the one part, and the corresponding edge a on the other part, and combined with the die C and punch E, and in such relative position thereto that the whole will operate in the manner substantially as set forth.

F. A. RICH,
H. W. BASSETT.
